UNITED STATES PATENT OFFICE.

JOSEF NICKL, OF OBERNDORF-ON-THE-NECKAR, GERMANY, ASSIGNOR TO WAFFEN-FABRIK MAUSER, AKTIENGESELLSCHAFT, OF OBERNDORF-ON-THE-NECKAR, GERMANY.

RECOIL-LOADING PISTOL.

1,413,184.

Specification of Letters Patent. Patented Apr. 18, 1922.

Application filed June 16, 1921. Serial No. 478,209.

To all whom it may concern:

Be it known that I, JOSEF NICKL, engineer, a citizen of the German Republic, residing at No. 8 of Hauptstrasse, in the city 5 of Oberndorf-on-the-Neckar, Germany, have invented certain new and useful Improvements in Recoil-Loading Pistols (for which I have filed application in Germany, April 12, 1916, and April 13, 1916; Czecho-Slo-10 vakia, Dec. 30, 1919; Poland, March 26, 1920; Hungary, January 13, 1920, and Roumania, March 19, 1920), of which the following is a specification.

My invention relates to a recoil-loading 15 pistol having a hammer-actuated firing-pin and a locking pawl or detent which, when the last cartridge of the magazine has been spent and the latter has been drawn out of the pistol, acts to retain the breech-slide in 20 its rearmost position.

The object of my invention is to provide a pistol of the kind in which the magazine holder is utilized to act or serve as a double spring for both the detent and the hammer. 25 To this end the inner or upper end of the magazine holder is shaped to form a double or two-armed spring having a wider arm for the hammer and a narrower arm for the detent. To allow of an extreme width to be 30 given to the former the two arms or springs are disposed in staggered relation that is to say, in juxtaposition and the one displaced in advance or in front of the other. In the old art locking pawls or detents were usually 35 mounted on pins which are rigidly and undetachably connected with the grip-stock, so that neither the pin nor said detent could be removed for repair or for any other reason without dismounting at the same 40 time the pistol in all its constituent parts. In order to do away with this inconvenience and to afford at the same time an easy way for properly mounting the detent and its spring so that they are in correct engagement, the said detent or locking pawl is carried by a detachable pin having a head which, when properly mounted lies flush 45 with the face of the grip-stock in a recess made for the purpose in one of the lateral 50 guiding ribs for the breech-slide. Hence on removal of the breech-slide there is no difficulty in removing the pin and the detent from the grip-stock and mounting same again so that they are duly engaged for correct co-action.

I have shown in the accompanying drawings one constructional embodiment of my invention only, but it is to be understood that my invention is not to be confined to that particular form. 60

In the drawings:

Figure 1 is a side elevation of the pistol with the improved detent mechanism partly in section,

Figure 2 is a rear view of the same with 65 the handle casing in section,

Figures 3 and 4 are a side view and a rear view respectively of the magazine holder,

Figure 5 is a complete side elevation of 70 the pistol with a few parts in section,

Figure 6 is a rear view of the grip-stock,

Figures 7 and 8 are a side view and a top view, respectively, of the locking pawl or detent,

Figure 9 shows the removable pin on 75 which the said detent is mounted, in three different positions.

In the pistol shown the breech-slide *a* is guided on the grip-stock *b*. Upon firing the said slide runs backwards or recoils acting 80 thereby to eject the empty cartridge, to cock the hammer *c* and, on its return to the inward or forward position, to introduce a fresh cartridge from the magazine into the barrel. In order to secure the magazine in 85 its position within the handle of the pistol a holder *d* is provided, as usual, having a nose *e* at the lower or outer end to lock the bottom plate of the magazine and to thereby hold the magazine in its proper position 90 within the handle. The magazine holder is inserted in a recess *i* of a downwardly projecting part of the grip-stock. According to my invention the said holder comprises a wide resilient arm or spring *f* for the hammer *c* and a narrow resilient arm or spring 95 *g* for the locking pawl or detent *h*. The two arms or springs *f* and *g* are disposed in staggered relation or displaced sideways one above or in front of the other (see Figures 3 100 and 4) whereby the aforeside advantages are obtained.

The locking pawl or detent *h* is pivotally mounted in the rear part of the grip-stock *b* and had a lateral projection or nose *m* at 105 its rear end. The front end *o* of said detent or pawl projects into the opening for the magazine and is kept in an elevated position by the magazine against the action of the resilient arm or spring *g*, so that the said 110

nose *m* does not impede the reciprocatory movement of the breech-slide *a* after firing. The breech-slide *a*, however is retained by the feeding plate of the magazine in its rear position after the last cartridge of the magazine has been fired, as is well-known in pistols of this type.

In removing the empty magazine from the pistol the pawl or detent *h* enters a recess or notch of the breech-slide, locking the same in the rear position (in lieu of the feeding plate which is removed together with the magazine), so that, after the insertion of a newly filled magazine, the loading operation takes place at once since the pawl or detent then is again in its inoperative position and the breech-slide free to run to its forward position.

According to my invention the pawl or detent is mounted on a removable pin *p* having its front end shaped so as to form a head *q* which, when the pin is being inserted in the two holes provided for the purpose of the grip-stock, engages in a correspondingly shaped recess cut in the guiding rib *r* of the grip-stock, so as to be in countersunk relation with the grip-stock. The head of the pin *p* is cut away or recessed at *s*, Figure 9, so that a small tool or the like may easily be brought in engagement therewith to lift and remove the pin from its seat in the grip-stock.

I claim as my invention:

1. In a recoil-loading pistol, the combination of a barrel, a grip-stock, a breech-slide guided on said grip-stock, a hammer, a pawl or detent for locking said breech-slide in its rear position, a cartridge magazine, and a holder locking the magazine in the pistol handle and comprising two resilient arms or springs in engagement with the said hammer and the said detent respectively.

2. In a recoil-loading pistol, the combination of a barrel, a grip-stock, a breech-slide, a hammer, a detent, a cartridge magazine, and a holder for the magazine having two juxtaposed resilient arms or springs, one arranged in advance of the other, one spring mounted to exert pressure on the hammer, and the other spring to exert pressure on the detent. 45

3. In a recoil-loading pistol, the combination, with a breech-slide, a detent for holding it in its rear position, and a hammer, of a magazine holder having two resilient arms or springs of different lengths disposed one in advance of the other; the longer spring being arranged to engage the detent, and the shorter spring, arranged 55 to engage the hammer, substantially as described and shown.

4. In a recoil-loading pistol, the combination of a barrel, a grip-stock, a breech-slide, a hammer, a pawl or detent for locking 65 said breech-slide, a cartridge magazine, a holder for securing the magazine in place having two resilient arms or springs for engaging the hammer and the detent, and a removable pin carrying said pawl or detent. 70

5. In a recoil-loading pistol, the combination of a barrel, a grip-stock, a breech-slide, a hammer, a detent for locking said breech-slide, a magazine, a holder for securing the magazine in place having two 75 resilient arms or springs for engaging the hammer and the detent respectively, and a removable pin carrying said detent and having a head in countersunk relation to the said grip-stock. 40

In testimony whereof I affix my signature in presence of two witnesses.

JOSEF NICKL.
